LIQUID FUEL BURNER

John Carlberg, Hartford, Conn., assignor to The
Silent Glow Oil Burner Corporation, Hartford,
Conn., a corporation of Connecticut

Application March 1, 1933, Serial No. 659,134

3 Claims. (Cl. 158—28)

This invention relates to liquid fuel burners, being more particularly concerned with the control of such burners during the starting thereof.

The invention will be best understood by reference to the following description when taken in connection with the accompanying illustration of one specific embodiment thereof, while its scope will be more particularly pointed out in the appended claims.

10 In the drawings:—

Fig. 1 is a side elevation of a liquid fuel burner with its principal working parts and embodying one form of the invention;

15 Fig. 2 is an enlarged sectional elevation, taken through the main solenoid-operated controlling valve and the companion auxiliary high and low fire valve;

20 Fig. 3 is a cross-sectional plan of a portion of the auxiliary valve and metering valves as shown in Fig. 2;

Fig. 4 shows in perspective the plunger for the auxiliary valve;

25 Fig. 5 is similar to Fig. 3 but showing a modified form of metering valve;

Fig. 6 is a simplified diagrammatic view of the electrical connections; and

Fig. 7 is a more elaborate diagrammatic view.

Referring to the drawings and to the embodiment of the invention selected for illustrative purposes, the apparatus comprises a conventional type of rotary centrifugal burner having a rotary cup 11 to which liquid fuel (herein for descriptive purposes referred to as oil) is fed and by which it is delivered in more or less atomized form to the combustion chamber of a furnace (not shown).

The cup is fixedly secured by means of a spider member 13 to a driving shaft 15 driven by the electric motor 17, oil being entered into the rear open end of the cup through the delivery pipe 19 and discharged from the open and somewhat flared mouth of the cup. At or adjacent the mouth of the cup there is maintained a gas ignition flame 21 which, if desired, may be automatically expanded and contracted with the starting and stopping of the burner. The mouth of the cup projects slightly beyond the mouth of a surrounding air distributing nozzle 23 spaced from the cup and providing an annular air passage communicating with the discharge end of a fan, the housing for which is shown at 25, and which is also driven by the motor 17.

Oil is supplied from a main tank through a pipe connection 27 to a pump 29, also driven by the motor 17. The pump delivers the oil through

the discharge pipe 31 and pipe connection 33 to a filter 34 and thence through the pipe connection 35 to main and auxiliary control valves 37 and 39, from the latter of which it passes through the pipe connection 41 and the delivery pipe 19 to the cup 11.

5 The pump discharge 31 has connected to it a relief valve 43 to return excess oil to the tank and the pipe connection 35 is provided with a pressure gauge 45. The control panel 47 carrying relay switches and other electrical control devices for the automatic operation of the burner is mounted on the frame of the apparatus adjacent the casing of the motor 17.

10 In the operation of an oil burner of this type, it is common practice when the motor is started, as by the functioning of a room thermostat, to defer the delivery of oil to the cup for a short interval to permit the cup to attain full speed and then to open the main oil valve, whereupon a full 15 supply of oil is delivered to the cup. This method of starting is apt to be and often is accompanied by some difficulty in effecting a quick ignition of the large body of oil delivered to the cup. The sudden introduction of a relatively large supply 20 of oil to the high speed rotary cup momentarily checks the smooth and even delivery of the oil and interferes with the proper atomization, and a substantial interval of time elapses before 25 equilibrium is established and the cup begins to 30 function in effecting the required degree of atomization. During this interval a substantial amount of unignited oil has been delivered to the combustion chamber, so that a backfire or puff of greater or less intensity frequently 35 accompanies this method of starting the burner, especially if started cold.

15 I have found that if, when the cup is first started into operation by the starting up of the motor, a relatively small supply of oil is delivered 40 to the cup, the required atomizing action may be immediately established and maintained without the disturbance referred to, an even, uniform delivery of the oil is at once effected, and a smooth and instantaneous ignition of the oil 45 is almost invariably had without backfiring or like disturbances.

20 A noiseless ignition, however, free from backfire and explosions or what is termed a "soft start," is best promoted by presenting initially to 50 the ignition agencies a relatively rich mixture of atomized oil and air, that is, one which is much richer than that under which the burner is to operate in normal running conditions after combustion has been initiated,—a thin mixture, or

one having a superabundance of air, possessing higher explosive properties than one in which there is an abnormal proportion of oil. This condition of noiseless ignition is further insured 5 in the present invention by providing for the delivery from the cup to the combustion chamber of the oil, although at the low rate of supply, substantially at the time the motor and fan first start into operation and before the latter has had 10 opportunity to build up its normal supply of air, so that the most favorable conditions for a "soft start" as well as for a quick start are created at the outset and in the initial stages of fan and 15 motor acceleration when the air supply, while rapidly increasing, is very restricted in amount and abnormally low as compared with the amount of oil supply.

The construction of the main and auxiliary 20 valves (shown in detail in Figs. 2, 3, and 4) and the electrical control of said valves (Fig. 6) herein provide for the initial delivery of oil to the cup when first started at a relatively low and adjustable rate, providing a low starting fire, this being followed after the lapse of a short interval 25 by the delivery of oil to the cup at a relatively high and also adjustable rate, providing a high fire for normal operation of the burner.

Referring to Figs. 2, 3, and 4, the main control 30 valve comprises a casing having the admission port 49 communicating with the supply pipe connection 35 and opening into a delivery port 51. When the burner is out of operation, the port 51 is closed by the tapered head 53 of a valve stem 55 which head rests in a seat provided at the 35 mouth of the port 51. The stem 55 fits loosely in the axial bore of the solenoid plunger 57 projecting somewhat above the top of the latter and terminating in an enlargement 59. The plunger is slidably mounted in the valve casing and in a 40 tubular, non-magnetic cap 60 projecting thereabove and is subject to the magnetic field of a surrounding magnet winding 61 covered by the protecting cap 63. When the winding is energized on the starting of the burner the plunger 45 is lifted, striking the enlargement 59, raising the valve 53 and opening wide the delivery port 51 to the oil delivered by the pump. When the winding is deenergized, the plunger drops by gravity, engaging the tapered valve head and 50 forcing it to its seat to close the delivery port.

The delivery port 51 has the pipe connection 65 to the casing for the auxiliary valve 39, which connection communicates with the admission port 67, the latter opening into a main delivery 55 port 69. When the burner is out of operation the port 69 is closed by the tapered head 71 of the valve stem 73, similar to the stem 55, and adapted to be actuated by a plunger 75 slideable in the casing 39 and the tubular cap 76. The 60 plunger is controlled by the magnet winding 77 having the protecting cap 79, so that the valve operates in a manner similar to the described operation of the main control valve.

The delivery port 69 communicates with the 65 delivery chamber 81 near the bottom of the valve casing 39, the delivery chamber in turn communicating with the pipe connection 46 leading to the cup.

When the magnet winding 77 is energized, the 70 valve 71 is lifted, rendering available the full area of its delivery port for the supply of oil to the burner. When the winding is deenergized, the valve 71 is caused by the plunger 75 to close its delivery port, but means are provided in the 75 closed position of the valve for establishing

through a by-pass to the delivery chamber 81 a relatively small and regulatable amount of oil. To this end the lower part of the plunger overlying the port 67 in the deenergized condition of the magnet winding has a square or other non-circular cross-sectional shape, and there is provided also confronting the squared lower end of the plunger a second or by-pass port 83 which also communicates with the delivery chamber 81 through the connecting port 85. Even with the 10 auxiliary valve 74 closed, therefore, a quantity of oil is free to flow from the port 67 under and around the plunger body into the port 83 and to the cup at a rate dependent upon the cross-sectional area of the passages provided. This 15 auxiliary or by-pass supply is designed to provide the initial or low fire supply heretofore referred to.

The ports 67, 83, and 85, for better understanding, are shown in Fig. 2 as if located in the same 20 vertical plane instead of as they are shown in Figs. 3 and 5 and as they actually appear in plan.

Means are herein provided for adjusting the 25 by-pass supply to suit the particular conditions pertaining in any given burner and also to adjust the high fire or normal supply and to adjust each with relation to the other. For this purpose there is provided between the ports 83 and 85 a metering valve comprising a pin 87 fitting more or less 30 loosely in a bore transverse the port 83 and having a projecting head, in the end of which there is formed a longitudinal V-shaped groove increasing in depth toward the end of the head and merging into a circular cross-section at a point 35 removed from its tip. The pin is carried by a member threaded into the side of the valve casing and having a projecting head 89 at the front of the casing (Fig. 1) by which its position may be adjusted. Between the head and the threaded 40 portion the pin has an enlarged tapered shoulder 88 (Fig. 3) adapted to be brought to a positive seat to entirely close the port. By the adjustment referred to, the end of the metering pin may be projected more or less between the ports 83 and 45 85, thereby providing for an accurate, graduated control of the available port cross-sectional area and adjusting the rate of low fire supply from what is permitted by the full cross-sectional area of the ports 85 and 83 to a point where, if desired, the supply is completely cut off by the closure of said ports.

To regulate the main oil supply a similar metering valve 91 having the external adjusting head 93 is provided in such a position that it may be 55 projected across the port 67 and adjust the opening of that port to any extent desired.

Accordingly, when the valve 71 is closed a low 60 fire supply of oil may pass the valve at a rate fixed by the metering valve 87, and when the valve is opened a high fire supply may pass, comprising not only the low fire supply but additionally the main supply passing through the delivery port 69, the high fire supply being limited by the adjustment of the metering valve 91.

For installations requiring a relatively large 65 consumption of oil, metering valves, such as are shown in Fig. 5, may be employed in which a tapered valve head 92 replaces the grooved pin, the head being cooperatively related to a correspondingly tapered seat to open or close the port.

The properly timed control of the valves is effected by electrical connections, which in simplified form may be represented in Fig. 6. Current is supplied to the apparatus from the main 75

conductors 93, 95 under the control of the usual form of room thermostat 97. When the thermostat acts to close the circuit, the motor, which is connected in shunt thereto, is energized, the cup is started rotating, and simultaneously there is also energized the winding 61 for the main valve 37, thereby permitting a supply of oil to be simultaneously delivered through the by-pass in the auxiliary valve 39 at a relatively low rate determined by the adjustment of the metering valve 87.

The winding 77 for actuating the auxiliary valve 39 is in a shunt circuit 99 which at the time referred to remains broken by the switch 101, not being closed until the latter is actuated. The switch is herein shown as representative of any suitable, time-actuated, circuit-changing device, and comprises a sealed glass tube containing a small body of mercury and pivotally mounted so that it may be tipped to an inclined position in which the mercury electrically connects two terminals, the latter sealed in the tube at one end thereof but externally connected to the two sides of the circuit 99. When tilted to a reverse inclination (as shown in the drawings), the mercury flows to the opposite end of the tube, thereby holding the circuit open.

To actuate the switch, the latter is adapted to be moved to one position or the other by the bending movement of a bi-metallic thermostatic strip 103, the lower end of which is fixed and the upper end of which is in engagement with the switch. Surrounding the strip there is a heating coil 105 which is also in shunt across the main circuit 93, 95. When the main circuit is opened and the burner out of operation, the switch 101 is in the open position shown in Fig. 5. When the thermostat acts to close the circuit for starting the cup into rotation with the low fire supply as already described, current passes through the heating coil 105, gradually raising the temperature of the bi-metallic strip 103, and finally, after the lapse of an interval, causing the latter to flex somewhat, assuming a position as is shown in dotted lines in Fig. 6. This tilts the switch to an inclination, closing the circuit 99, energizing the winding 77, opening the valve 39, and delivering to the cup the high fire oil supply at a rate determined by the metering valve 81.

The interval elapsing after the starting of the motor and before the actuation of the timing switch for the auxiliary valve may be anything required for the characteristics of the particular burner to which it is applied and may be predetermined by the design or selection of the winding 105 and the thermostatic strip. By way merely of a numerical example such interval may be thirty seconds.

In the practical installation of the high and low fire control where safety devices are employed designed to stop the delivery of fuel on failure to establish normal conditions of combustion after the lapse of a safe interval of time following the starting of the motor, or on failure to maintain such condition for a safe interval, it becomes desirable to coordinate the timing of the low and high fire control with such safety devices, so that the cup may function through the desired successive stages and the safety devices will act to stop the motor only after the lapse of a further and substantial interval of time following the increase in the rate of fuel supply resulting from the opening of the auxiliary valve. An arrangement designed to accomplish this is shown conventionally and diagrammatically in Fig. 7.

Referring to Fig. 7, there is provided a circuit closing device 107, herein termed, merely for purposes of designation, the main switch, this being of the tubular mercury type already described. This switch is normally open (as shown in Fig. 7) when the burner is out of operation. When the thermostat 97 is actuated, the switch 107 is closed by means of a magnet 109. The latter is connected to the main 93 by a conductor 111 and is included in a circuit comprising the conductor 10 113, the normally closed switch 115, conductors 117 and 119, heating coil 121 and main 95. The closing of the switch 107 starts the motor, serving to connect the motor to the main 93 through conductors 123 and 125 and to main 95 through 15 conductors 127 and 129. It also simultaneously opens the main oil valve 37, the magnet coil 61 for which is connected through conductor 131 to conductor 125 and through conductor 133 to conductor 129.

This starts the rotation of the cup and the delivery of oil at the low fire rate. The heating coil 105 for the timing switch 101 is simultaneously cut into circuit, one terminal being connected to the main 95 through conductors 135 and 129 and 25 the opposite terminal to main 93 through conductors 137 and 117, switch 115, conductor 113, magnet 109 and conductor 111.

After the lapse of a selected time interval, thirty seconds for example, the timing switch 30 30 net winding 77 for the low and high fire valve 39 and opening the latter to provide a full rate of oil supply to the fuel distributing device or cup. One terminal of the winding 77 is connected to the 35 main 93 through conductor 131 and the path already described for winding 61, and the opposite terminal on closure of the timing switch is connected to main 95 through conductors 139 and 141, switch 101, and conductors 143 and 129. 40

The main 93 passes through a safety switch 145 which is normally held closed by a detent comprising a bimetallic thermostatic strip 147, the latter within the influence of the heating coil 121. When operation of the apparatus is initiated by the action of the thermostat, current passes through the heating coil, and if continued for a sufficient interval the strip is caused to flex, the safety switch is tripped, the circuit of the motor and various electrical control devices 50 opened, and further operation of the motor and the delivery of oil is stopped until the safety switch is reset by hand.

If normal conditions of combustion, however, are established within the interval required for 55 the tripping action of the thermostatic detent, the heating coil 121 is automatically cut out of circuit together with the heating coil 105 for the timing switch 101, and circuits excluding said heating coils are simultaneously established for 60 energizing the coil 77 of the valve 39 and for holding the main switch 107 closed. For this purpose there is provided a combustion responsive device 149 exposed to the products of combustion in the combustion chamber or the flue 65 of the furnace and receiving heat therefrom. This may be of the well-known thermostat type and adapted, when such a temperature is reached as indicates suitable or normal conditions of combustion, provided it is attained before the safety 70 switch opens, to close normally open contacts at the responsive device and complete a circuit through magnet 151, the latter connected to open the combustion switch 115 and close its companion switch 153.

One terminal of the magnet 151 is connected to main 95 through the conductor 155, the combustion responsive device 149, and conductors 157, 159, and 129, and the opposite terminal is connected to the main 93 through conductor 161. The opening of the switch 115 cuts out of circuit the heating coils 105 and 121. The simultaneous closing of the switch 153 energizes a holding magnet 163 which retains the main switch 107 closed, and also connects one terminal of magnet 77 directly to the main 95. The holding magnet 163 has one terminal connected to main 93 through conductor 161 when switch 153 is closed, the opposite terminal being connected to main 95 through conductors 165 and 167, switch 153, and conductors 159 and 129. At the same time the conductor 139 for magnet 77 is also connected directly to main 95 by the conductor 167 and switch 153.

The timed action of the heating coil 121 may be predetermined by design of the coil and the cooperating thermostat detent, and should be such that the time interval required for its action when this coil is subjected to a continuous current flow is in excess of the time interval required for the actuation of the timing switch 101, so that the cup may receive oil at the low rate of delivery for a short interval, such, for example, as half a minute, and may thereafter receive oil for a further substantial interval, such, for example, as one minute, before the tripping device can act. This provides for the necessary time relation between control devices so that, after the opportunity is had for ignition with the low fire supply, there is a substantial interval in which combustion may develop under the high fire supply and the functioning temperature of the combustion responsive device be certainly reached, except in cases of abnormal function failure of the burner.

While I have herein shown and described for the purposes of illustration one specific embodiment of the invention, it is to be understood that this is submitted for illustrative purposes only and that extensive deviations and changes in the character and relation of the elements employed and other applications of the means herein disclosed may be made, all without departing from the spirit of the invention.

I claim:

1. In combination with a liquid fuel burner having a motor driven rotary distributing device and a fuel feeding means therefor, a control circuit including said motor, a main thermal control switch, a first magnetic valve which is opened when energized to feed fuel at a relatively low rate, a second magnetic valve which is opened when energized to feed fuel at a relatively high rate, a first thermal time switch having a heater and operative when energized for a predetermined time to terminate burner operation, a second thermal time switch having a heater and op-

erative when energized for a time period less than said predetermined time to energize said second valve, and a combustion responsive switching mechanism controlling burner operation and cooperating with the main control switch upon closure of the latter in response to a demand for heat to energize said motor, said first magnetic valve, and said thermal time switches, and in response to the establishment of combustion within said predetermined time to deenergize said thermal time switches, to maintain the motor energized, and to maintain or establish energization of said second valve.

2. In combination with a liquid fuel burner having a motor driven rotary distributing device and a fuel feeding means therefor with means to effect delivery of fuel to said distributing device at a relatively low rate, a control circuit including said motor, a main control switch, a valve with means to open the same to insure delivery of fuel at a relatively high rate, a first thermal time controlled switch operative when energized for a predetermined time to terminate burner operation, a second time controlled switch operative when energized for a time period less than said predetermined time to open said valve, and a combustion responsive switching mechanism controlling burner operation and cooperating with the main control switch upon closure of the latter in response to a demand for heat to energize said motor and said time controlled switches and in response to the establishment of combustion within said predetermined time to deenergize said time controlled switches to maintain the motor energized and said valve open.

3. In combination with a liquid fuel burner having a motor driven rotary distributing device and fuel feeding means with means to effect delivery of fuel to said distributing device at a relatively low rate, a control circuit including said motor, a main control switch, controlling means for insuring delivery of fuel at a relatively high rate, a first time controlled switch with timing means operative when energized for a predetermined time to terminate burner operation, a second time controlled switch with timing means operative when energized for a time period less than said predetermined time to actuate said high delivery control means, and a combustion responsive switching mechanism controlling burner operation and cooperating with the main control switch upon closure of the latter in response to a demand for heat to energize said motor and both said timing means and in response to the establishment of combustion within said predetermined time to deenergize said timing means to maintain the motor energized and to maintain said relatively high rate of fuel delivery.

JOHN CARLBERG. 50
